UNITED STATES PATENT OFFICE.

EDWARD J. ASZKLAR, OF PLANTSVILLE, CONNECTICUT.

CLAM OPENER.

Application filed February 1, 1923. Serial No. 616,365.

To all whom it may concern:

Be it known that EDWARD J. ASZKLAR, a citizen of the United States of America, residing at Plantsville, in the county of Hartford and State of Connecticut, has invented new and useful Improvements in Clam Openers, of which the following is a specification.

The object of the invention is to provide an apparatus for facilitating the opening of clams and like shell fish under conditions minimizing the inconveniences and risk of the operator and without the expenditure of a considerable portion of the time ordinarily required in the operation; and with this object in view the invention consists in a construction and combination of parts of which a preferred embodiment is shown in the accompanying drawings, wherein:—

20 Figure 1 is a side view partly broken away of an apparatus embodying the invention.

Figure 2 is a front end view thereof.

25 Figure 3 is a section on the plane indicated by the line 3—3 of Figure 1.

Figures 4 and 5 are detail views respectively of the entering element and one of the spreading elements of the opener head.

Figure 6 is a rear end elevational view.

30 Figure 7 is a perspective view showing the lower of the operating levers.

Figure 8 is a similar view showing the upper of the operating levers.

The apparatus embodies essentially a head 35 10 adapted for engagement with and penetration of a shell of the clam or like shell fish, carried by operating levers 11 and 12 which are pivotally mounted at one end between uprights 13 and are movable at the 40 other end in a guide formed by the uprights 14, said uprights in the construction illustrated being supported by a base 15 having a shell seat 16 designed to receive one edge of a clam shell during the operation 45 of opening the same.

The head consists of a blade or penetrating element 17 of comparatively thin material having an arrow or dart head 18 for penetration between the edges of the shell, and spreader members 19 constituting jaws arranged at opposite sides of the penetrating member or blade and adapted at their lower ends to be carried into the shell by the penetrating member and then to be separated to open or spread the shell. The 50 blade or penetrating member is secured by

means of a stud 20 at its upper end to the lever 11 and the lever 12 is provided with a yoke 21 straddling the blade with its sides in engagement with hooks 22 at the 60 upper ends of the jaws 19 so that the jaws are free to swing outwardly at their lower ends upon the sides of the yoke as fulcrums. The jaws are yieldingly held in operative 65 relation with the blade by means of a contractile spring 23 and at their free ends are disposed adjacent to protecting shoulders 24 on the arrow head of the blade. Also a positioning pin 25 is carried by the 70 blade with its terminals in engagement with outwardly bowed portions of the jaws 19.

With a clam disposed in the seat 16 the operating lever should be pushed downward and the reduced point of the penetrating blade forced between the edges of the shell to separate the same and permit the entrance of the free ends of the spreading elements or jaws 19. Preferably the standard 14 is provided with stop pins 26 in the path of a transverse pin 27 on the upper lever 11 80 which is preferably somewhat shorter than the lever 12, and when the pin 27 comes in contact with the stop pins 26 to thereby check the movement of the lever carrying the shell penetrating element, the latter by 85 this time having sufficiently entered the shell of the clam, the hand of the operator will readily slip to the lever 12 and by continuing the movement thereof will cause the bowed portions of the jaws 19, acting as cams in relation to the pin 25 and in opposition to the spring 23 to spread the lower free 90 ends of the jaws and thereby open the shell of the clam. The lower or operative extremities of the jaws are reduced to five inches 95 and are outwardly directed on curved lines so that the edges follow the inner surfaces of the shell members and hence cut the eye of the clam loose from the shell and release it for removal.

100 Having described the invention, what is claimed as new and useful is:—

1. An apparatus for opening clams and the like having a head consisting of oppositely movable jaws and an intermediate shell penetrating member for insertion between the edges of the shell, and means for successively advancing the head and spreading said jaws.

110 2. An apparatus for opening clams and the like having a head consisting of oppositely movable jaws and an intermediate

shell penetrating member for insertion between the edges of the shell, and means for successively advancing the head and spreading said jaws, and consisting of simultaneously and independently movable levers respectively connected with the jaws and said intermediate member.

3. An apparatus for opening clams and the like having a head consisting of oppositely movable jaws and an intermediate shell penetrating member for insertion between the edges of the shell, and means for successively advancing the head and spreading said jaws, the jaws having blade-like terminals for traversing the inner surfaces of the shell members.

4. An apparatus for opening clams and the like having a head consisting of oppositely movable jaws and an intermediate shell penetrating member for insertion between the edges of the shell, and means for successively advancing the head and spreading said jaws, said jaws having outwardly deflected blade-like terminals for traversing the inner surfaces of the shell members.

5. An apparatus for opening clams and the like having a head consisting of oppositely movable jaws and an intermediate shell penetrating member for insertion between the edges of the shell, and means for successively advancing the head and spreading said jaws, said jaws being yieldingly held with their free ends in closed relation with said intermediate member.

6. An apparatus for opening clams and the like having a head consisting of oppositely movable jaws and an intermediate shell penetrating member for insertion between the edges of the shell, and means for successively advancing the head and spreading said jaws, said jaws being yieldingly held with their free ends in closed relation with said intermediate member and having cam faces cooperating with a spreader pin carried by the intermediate member.

7. An apparatus for opening clams and the like having a head consisting of oppositely movable jaws and an intermediate shell penetrating member for insertion between the edges of the shell, and means for successively advancing the head and spreading said jaws, the intermediate member having shoulders for protecting the free ends of the jaws.

8. An apparatus for opening clams and the like having a head consisting of oppositely movable jaws and an intermediate shell penetrating member for insertion between the edges of the shell, and means for successively advancing the head and spreading said jaws, the intermediate member being provided with an arrow head terminal having shoulders disposed in normal overlapping relation with the free ends of said jaws.

In testimony whereof he affixes his signature.

EDWARD J. ASZKLAR.
